United States Patent Office.

WILLIAM W. USTICK, OF LA CROSSE, WISCONSIN.

Letters Patent No. 80,245, dated July 21, 1868.

IMPROVED APPARATUS FOR CUTTING AND MITRING PRINTERS' RULES.

The Schedule referred to in these Letters Patent and making part of the same.

TO ALL WHOM IT MAY CONCERN:

Be it known that I, WILLIAM W. USTICK, of La Crosse, in the county of La Crosse, and State of Wisconsin, have invented a new and improved Apparatus for Mitring and Cutting Printers' Rules; and I do hereby declare that the following is a full and exact description thereof, reference being had to the accompanying drawings, and to the letters of reference marked thereon.

The nature of my invention mainly consists in an apparatus for cutting printers' rules to form mitres, &c., by means of files or equivalent cutters, arranged and operating as hereinafter described.

In the accompanying drawings, which make a part of this specification—

Figure 1 is an isometrical view of the apparatus.

Figure 2 is a vertical longitudinal section of the same.

Figure 3 is an isometrical view of the mitring-tool B.

Figure 4 is a like view of the squaring-tool C.

Figure 5 is an isometrical view of the gauge D.

Figure 6 is a like view of the clamp F.

Like letters in all the figures indicate the same parts.

A is a box for holding the rules to be cut, and the tools for mitring and squaring the same. It has a vertical longitudinal groove, *a*, for holding the rule *a'* to be mitred or squared, and a cross-groove, *a'*², at right angles thereto, in which the mitring-tool B is moved backward and forward to form the mitres, or the tool C for squaring ends of rules. The former tool is shown in detail in fig. 3, and the latter in fig. 6. The cutter *b* of the mitring-tool B has bevelled edges *1 1*, at right angles to each other, and at equal angles to a vertical line drawn through the junction of the two edges. These edges have file-teeth throughout their whole length, as represented in fig. 3. The cutter *b* is confined, by means of screws *c c*, in the rebate *d* of the stock *b'*. The cutter *e* of the squaring-tool C is similarly constructed and arranged, except as to the form of the cutting-edge. It has a file-edge, *f*, which is at an acute angle with the sides of the stock *e'* and of the cutter, so as to give facility to the operation of the latter in cutting off or squaring the ends of rules. The box A, I usually construct of cast iron. If desired, the portion of the box from 3 to 4 may be left off at the left hand of the cross-groove *a'*.

D is a gauge at the bottom of the groove *a*, for determining the lengths of the rules. It is adjustable by means of the set-screw E in the clamp F, which slides freely in the longitudinal grooves *g g*, as seen in figs. 1 and 2. G is a scale for facilitating the adjustment of the said gauge D, there being vertical lines from the figures to the bottom of the groove *a*, to which the front edge of the gauge is respectively set. F' is a clamp for securing the front end of the rule against the bottom of the groove *a* while it is cut or mitred. The said clamp is held down by means of the spring H, beneath the cross-piece I, and it is raised at pleasure by means of the knob J on the vertical rod *h*, when a rule is to be withdrawn or one put in place. The gauge D and clamp F are shown respectively in figs. 5 and 6.

The operation is as follows:

In the mitring process, a rule is confined in the position shown in figs. 1 and 2, in the manner hereinbefore described, with its rear end against the gauge D, and the mitring-tool B is pushed backward and forward in the cross-groove *a'*² until the cutter *b* has cut through the rule, forming a mitre. When the point of the cutter has descended a little below the bottom side of the rule, so that the wire-edges of the lower corners are removed or smoothed off by the action of the file-teeth, the lower edge of the stock *b* is arrested by the bottom of the groove *a'*², or the guide strip *a'*³, which serves for a ready adjustment by placing a strip of paper beneath it, or the removal of the same, the said strip being confined, by means of screws, to the bottom of the groove. Cutting off and squaring rules is performed in like manner, by means of the tool C.

The tools B and C may be operated by means of a crank and pitman, or other device, if desired.

Instead of the file-teeth to the cutters, there may be a succession of bits confined to the cutter-stocks, in any convenient manner, or attached to the periphery of a wheel.

In the place of the spring H, a lever, cam, or wedge may be substituted, or a vertical screw may be used for forcing the clamp on the rule and elevating it therefrom.

What I claim as my invention, and desire to secure by Letters Patent, is—

1. The combination of the file-formed cutter b with the stock B, when arranged to operate substantially as described and for the purpose set forth.

2. The improved apparatus herein described, when its several parts are constructed and arranged with relation to each other, in the manner and for the purpose set forth.

3. The combination of the file-formed cutter e with the stock B, when constructed as and for the purpose specified.

In testimony whereof, I have hereunto set my hand and affixed my seal, this 4th day of December, 1867.

W. W. USTICK. [L. s.]
